2 SHEETS—SHEET 2.

INVENTOR:

BENJAMIN B. BETTS,
by Edward E. Long, gen.

UNITED STATES PATENT OFFICE.

BENJAMIN B. BETTS, OF ST. LOUIS, MISSOURI.

RAIL-ANTICREEPER.

1,195,770.

Specification of Letters Patent. Patented Aug. 22, 1916.

Application filed March 6, 1916. Serial No. 82,370.

To all whom it may concern:

Be it known that I, BENJAMIN B. BETTS, a citizen of the United States, and resident of St. Louis, Missouri, have invented certain new and useful Improvements in Rail-Anticreepers, of which the following is a specification containing a full, clear, and exact description, reference being had to the accompanying drawings, forming a part hereof.

My invention relates to improvements in rail anti-creepers, and is directed to that type having an element which is clamped to the rail base, and an element for engagement with a tie, and my object is to construct a simple, inexpensive, durable and efficient means which will adapt itself to rails of different dimensions and so designed to prevent rail creeping, and is of such nature as to automatically tighten itself upon the rail in the event of creeping.

With the above and other objects, which will hereinafter be made clear, my improvement consists in the novel construction and arrangement of parts which are hereinafter fully, clearly and concisely set forth, pointed out in my claims, and illustrated by the accompanying drawings, in which—

Figure 1 is a plan of my improved device showing its relationship with a rail and tie which are shown only fragmentarily; Fig. 2 is an end view of a rail shown in section with a device embodying my improvement shown in position thereon; Fig. 3 is a sectional elevation showing the device of my invention in longitudinal section, and a rail in transverse section; Fig. 4 is a sectional plan of the device showing it in a position other than a right angle, to a rail which is shown in section, to illustrate its adaptability to rail bases of a lesser width than the lateral spacing of the rail base engaging elements of the device; Fig. 5 is a detail sectional elevation of the rail base and the device taken on the line 5—5 of Fig. 3; and Fig. 6 is a detail perspective of the wedge.

Referring by numerals to the accompanying drawings, 6 designates a tie or sleeper arranged for the support in a common manner of the rail 7 which is of ordinary construction, and having the usual base flanges 8 and 9.

10 designates the body portion of the device of my invention which is preferably of oblong shape and whose upper surface is 55 plane.

At the one end of the body portion 10 there is formed an integral jaw 11, the back wall 12 of which rises substantially at right angles to the body 10 but as shown in Fig. 60 4 is preferably convexed or curvilinear transversely of the jaw, the overhanging wall 13 of which, together with the plane upper face of the body 10, are shaped to conform with a rail base flange, that is the said overhanging wall 13 of the jaw 11 is inclined relative to the horizontal inwardly and upwardly with respect to the jaw, and in order to lend rigidity to this jaw, I form integrally therewith the strengthening ribs 14 paralleling the major axis of the device and a rib 15 extending between the ribs 14 located in a plane approximating the plane of the body 10.

Formed integrally with the body 10 and 75 extending laterally from the jaw 11 is a tie engaging bracket or element 16.

Arising from the body 10 in opposition to the back wall 12 of the jaw 11 and spaced therefrom a distance approximating an average rail base width, is a wall 17 which is provided with a curvilinear face extending at right angles to the body 10 of the device and inclined upwardly and away with respect to the opposing back wall 12 of the 85 jaw 11. That is, the wall 17 and the back wall 12 present convex faces to the edges of the rail base flanges 8 and 9. The vertical inclination of the wall 17 serves the double function of adapting the device to rail bases 90 of different widths, and providing a wedge action when the rail is seated to assist the clamping of the device to the rail base.

Extending laterally from the top of the wall 17 and thence upwardly and reversely 95 to overlie the said wall 17, and a considerable portion of the rail base flange 9, is a jaw 18, which is of much greater dimensions than the jaw 11, both vertically and transversely, whereby to receive between its uppermost overlapping portion and the rail base flange, a wedge 19, as well as to afford greater superficial area and strength, than the jaw 11. It is to be noted here that the

- body portion 10 lying next adjacent the jaw 18 is likewise increased in width or transverse dimensions over the remainder of the body. Like the jaw 11, the jaw 18 is provided with strengthening ribs 20 which extend from its free end around the bight underneath the jaw and merge into the body of the device at its approximate longitudinal center.
- 10 As shown in Figs. 2 and 3 the one margin 21 of the wedge and the bight 22 of the jaw 18 are arcuate in cross section, and as shown by dotted lines in Fig. 1 the arcuated margin 21 of the wedge and the bight 22 of the jaw 18 are disposed at an angle relative to the minor axis of the device so as to be out of parallelism with the rail.
- 15 The wedge as shown and as just described tapers lengthwise and also tapers transversely, its convexed or arcuated margin 21 having greater thickness than the wedge at its opposing margin.
- 20 In order only to reduce the weight I prefer to form channels 23 in the upper and lower faces of the wedge adjacent its arcuated margin, and to facilitate the insertion of the wedge between the rail base flange and the jaw 18, the forward margin of the wedge is chamfered, as shown in Fig. 5 at 25 24 and in order to provide drainage between the wedge and the upper surface of the rail base flange, I prefer to construct the bottom face of the wedge with an undulate surface 30 25 as shown in Fig. 5.
- 25 Arising from the rear end of the wedge, as clearly shown in Figs. 1, 2 and 5, is an integral projection extending above the plane of the upper face of the wedge forming a stop 26 which together with the jaw 18 forms 35 40 a means for limiting the movement or insertion of the wedge in one direction relative to the jaw.
- 30 At or near the end of the wedge, opposite the stop 26, adjacent the margin of the wedge opposite the arcuated portion 21, and in the upper face of the wedge there is a depression 27, forming a shoulder 28 arranged to be engaged by a lug 29 formed integral with the jaw 18 at its side opposite 35 40 the wedge entering side, and which lug is struck or depressed to seat to the rear of the shoulder 28 formed by the depression 27, whereby to prevent retrograde movement of the wedge.
- 45 It is to be observed that the inner overhanging margin of the portion 13 of the jaw 11, and the arcuated bight of the jaw 18, are laterally spaced a distance somewhat greater than the width of the rail base whereby to 50 55 permit of the placing of the device upon a rail by placing its body under the base of the rail, its one flange in the jaw 18, and then moving the entire device until the flange 8 is seated in the jaw 11 and the flange 60 65 9 is resting upon the vertically inclined wall 17. After the device has thus been placed upon the rail, it is moved to a position with the bracket 16 engaging an adjacent tie.
- If the rail base is of a lesser width than the lateral spacing of the walls 12 and 17, the entire device is moved into angular relationship with the rail as shown in Fig. 4 to such a position wherein the opposing walls 12 and 17 will engage the sides of the rail base flanges, it being understood of course, in this connection, that the entire device must be moved to a position with the bracket 16 engaging the tie.
- Whether the device be at right angles or at an obtuse angle relative to the rail as just described, the device is first manually placed as described, and then moved manually to cause the device to be frictionally held to the rail base by a wedging action of the walls 12 and 17. The wedge 19 is then forced into position between the rail flange 9 and the jaw 18, the chamfer 24 of the wedge serving to fully draw the wall 17 against the edge of the rail base flange, after which the wedge is forced into its full seated position with its stop 26 abutting the jaw 18. It will be apparent that the movement of the wedge as just described, by reason of its longitudinal taper forces the device laterally of the rail, and thus exerts compression between the walls 12 and 17, and jaws 11 and 18, and also by reason of the taper of the rail base and wedge exerts compression vertically between the jaw 18 and the body portion 10. After the wedge 100 has thus been fully seated and the device firmly clamped to the rail base, the operator strikes the lug 29 and moves it to a position behind the shoulder 28 of the wedge thus locking it in position.
- By reason of the taper of the rail base, it will be apparent that any movement of the rail, however slight, in the direction of travel of rolling stock, and toward the tie abutting the bracket 16, will of necessity 110 tend to move the entire device at a greater angle relative to the rail, and thus cause a further tightening of the wedge in its seat between the rail and the jaw 18.
- By reason of the arcuated bight of the jaw 18, and a correspondingly formed margin of the wedge, it will be apparent that the same wedge may be advantageously used on rail base flanges of different vertical dimensions within a reasonable range, and that 115 wedges of varying sizes may be used with the same device on rail bases whose vertical dimensions are outside of the range just recited.
- Having thus described my invention, what I claim as new therein and desire to secure by Letters-Patent of the United States, therefor is:
1. A rail anti-creeper comprising opposing walls for engagement with opposite margins 120

of the rail base, one of which walls is inclined relative to the vertical, and means for moving the anti-creeper vertically relative to a rail whereby to wedge the rail base between 5 said opposing walls.

2. A rail anti-creeper, comprising a pair of oppositely disposed walls for engagement with the side margins of a rail base, said walls being curvilinear from end to end 10 whereby to adapt the device to different widths of rail bases, one of said walls being inclined relative to the vertical, and means for moving the device vertically relative to the rail, whereby to clamp the device to the 15 rail between said opposing walls.

3. A rail anti-creeper, comprising opposing walls for engagement with opposite margins of the rail base, one of which walls is inclined relative to the vertical, means 20 for moving the anti-creeper vertically relative to a rail whereby to wedge the rail base between said opposing walls, and an element arranged to engage a fixed object on the road bed.

25 4. A rail anti-creeper, comprising a pair of oppositely disposed walls for engagement with the side margins of a rail base, said walls being curvilinear from end to end whereby to adapt the device to different 30 widths of rail bases, one of said walls being inclined relative to the vertical, means for moving the device vertically relative to the rail, whereby to clamp the device to the rail

between said opposing walls, and an element arranged to engage a fixed object on the 35 road bed.

5. A rail anti-creeper, comprising a body portion, an integral jaw at one end of said body portion, a vertically inclined wall arising from and integral with the body portion 40 in opposition to the back wall of said jaw, a second jaw integrally formed with said body portion and overhanging said vertically inclined wall, and a wedge for co-action 45 with said last mentioned jaw for moving the device both vertically and laterally relative to the rail.

6. A rail anti-creeper, comprising a body portion, an integral jaw at one end of said body portion, a vertically inclined wall arising from and integral with the body portion in opposition to the back wall of said jaw, a second jaw integrally formed with said body portion and overhanging said vertically inclined wall, a wedge for co-action 50 with said last mentioned jaw for moving the device both vertically and laterally relative to the rail, and integral means for securing the wedge immovably relative to the jaw.

In testimony whereof, I have signed my 60 name to this specification, in presence of two subscribing witnesses.

BENJAMIN B. BETTS.
